HARRY SWINGLEHURST, OF COLLINGSWOOD, NEW JERSEY, ASSIGNEE TO SCOTT & WILLIAMS, INC., OF BOSTON, MASSACHUSETTS, A CORPORATION OF NEW JERSEY.

YARN-CHANGING DEVICE FOR KNITTING-MACHINES.

1,093,362.

Specification of Letters Patent. Patented Apr. 14, 1914.

Application filed November 9, 1912. Serial No. 730,382.

To all whom it may concern:

Be it known that I, HARRY SWINGLEHURST, a citizen of the United States, residing at Collingswood, county of Camden, and 5 State of New Jersey, have invented a certain new and useful Yarn-Changing Device for Knitting-Machines, of which the following is a specification.

My invention relates to that class of yarn feeding devices for knitting machines in 10 which a yarn or yarns held in a position to be fed to the needles is adapted to be exchanged for another yarn or yarns, with due provision for maintaining the continuity 15 of the feed to the needles and for providing the necessary tension or absence of tension at different times upon the said yarns, as well as providing for the proper control of such yarns as may be idle or out of work. 20 To these ends my invention comprises movable yarn guides and means to operate them at predetermined times as well as devices for clamping and cutting the idle yarns between the knit fabric into which 25 they are no longer being fed and the said movable yarn guides, and devices for providing against the accidental displacement of the idle yarns during such times as they remain out of work.

30 In the accompanying drawings, Figure 1 is a plan of so much of a hosiery knitting machine as is necessary to illustrate the application thereto of my improved devices; Fig. 2 is a vertical axial section through the 35 yarn manipulating elements as applied to the said machine; Fig. 3 is a vertical section of the line III—III of Fig. 2.

As is usual in hosiery machines the yarn guide and control devices are operatively 40 associated with a latch ring or guard 1 disposed concentrically with the needle cylinder of the machine, said ring serving to prevent the closing of the latches opened by the previous loop upon the upward or advancing movement of the needles. At a point 45 in said ring at substantially the mean location of the knitting wave in the needles, which knitting wave has ordinarily a movement of oscillation with respect to the feed point depending upon the direction of rotation, a channel or throat 2 is formed in the latch guard ring. Through the said channel or opening the yarns are fed to the advanced needles, the open hooks of which pass near 50 the inner surface of the latch guard ring

when the needles are advanced by their cam. One side or corner of the said channel or throat may serve as a guide to determine the last point of contact with the yarn before it encounters the needles.

In a suitable two part bracket 3, which may be formed integrally with the latch guard ring at some distance above and outwardly from the throat 2, I mount a short horizontal shaft 4 upon which is strung a 65 series of movable yarn guide levers 5, the bracket 3 having stop rods 6 and 7, determining the amount of movement of each of the yarn guide levers 5 upon the shaft 4. Upon another short shaft 8, also journaled in said bracket, a series of actuator levers 9 corresponding in number to the yarn guide levers 5 is mounted. Each of the levers 9 is in contact with a spur or lug on the 70 yarn guide levers 5 and at the other end is 75 within the arc of motion of cams or pattern lugs on a drum journaled on the shaft 10 which may be the shaft upon which the latch guard structure and its attachments are pivoted.

As fully described in my application Serial No. 653,001 filed October 5, 1911, the cam drum for operating the movable yarn guides is operated at predetermined times by a mechanism comprising the ratchet 11.

When a yarn guide lever 5 is in a substantially vertical position the yarn or yarns guided in apertures in the end thereof is placed in the throat 2 in a position to be fed to the needles. This position of each of the yarn guide levers is normally caused by the stress of one of the series of springs 12 connecting each yarn guide lever with its actuating lever, but is interfered with by the cam lugs under the control of the ratchet 11, 95 in order to swing the yarn guide levers 5, except that one which is in operative position, into an inner or inoperative position, as plainly shown in Fig. 2.

Coöoperating with the yarn changing yarn guides I may provide on the interior of the surface defined by the needles, by which it will be understood I refer to a cylindrical surface coextensive with the needles, passing concentrically through the latch guard ring, an internal guide and clamp indicated generally at 14. This structure is mounted upon an integral or other extension of the latch guard ring passing upwardly, inwardly and then downwardly to a level near that

of the bottom of the latch guard ring, where it terminates in an anvil or plate 15 against which a movable clamp 16 pivoted on a stud 13 may be forced. Said plate 15 also carries the fixed blade 17 co-operating with a movable blade 18 to form a shear cutter. Blade 18 is mounted upon a vertical slide 19 moving in a channel 20 on the bracket 14. Said slide 19 is operated by a lever 10 arm 21 journaled at 22 on the latch guard ring, the other end of said lever taking against the cam drum to be operated by suitable cam lugs. It will be understood that the shear cutter is so disposed and that 15 the cam lugs are so adjusted as to cause the cutter to sever the yarn from an idle yarn guide whenever said yarn guide has been thrown from its operative to its inoperative position. Such movement of the yarn guide 20 causes the yarns to approach the center of the machine and further rotation of the machine carries the yarns attached to the fabric at the point where they were last knit under the fixed spring guide 23 on the face of the 25 plate or anvil 15 between the jaws formed by the clamp 16 and the plate 15, which are now open to receive said yarns, and thence into the open jaws of the cutter 17, 18, which is immediately actuated upon the yarns 30 reaching this point.

The tail of the clamp lever 16 takes between lugs on the slide 19 to effect the simultaneous closing of the clamp 15, 16 and the cutters 17, 18.

35 While I have found the above described mechanism which is substantially that disclosed in my said application highly efficient for the purpose of changing one yarn for another in the orderly operation of the machine, some difficulty has been experienced with the device when using certain kinds of yarn, especially under a slack knitting tension. This difficulty I have found to be due to the gradual slackening of the yarns between the source of supply (not shown) 40 and the clamp 15, 16, due to air currents and vibration of the machine, or to other causes.

As is usual in all knitting machines of this type the yarn from the supply bobbins 50 is passed downwardly through an overhead guide whence it may or may not be passed through fixed guides such as I have shown as comprising eyelets 26 in a plate 27 forming a part of bracket 3. From this point 55 the yarns are threaded through the openings in the yarn guide levers 5. It will be noticed that the actuation of a lever 5 swings the yarn about the nearest fixed guide above them, in this instance one of 60 the eyelets 26, as a center; and through an arc measured by the oscillation of the apertured end of the yarn guide levers.

The proper tension of the yarn when it is first given to the needles is of great importance, since if the yarn is too loose at

this time it may fail to engage the needles at the intended point. When attempting to control the point of change of one yarn for another within one or two needles about the circle of needles, rotating at high velocity with respect to the yarn throat 2, it is of the utmost importance that nothing should interfere with the timing of entrance of the yarn between the two certain needles intended to receive it, and delay caused by slackness in the yarn between the internal clamp and the guides 26 may defeat placing the yarn at the proper needles. Under aggravated conditions the yarn may sometimes fail to reach the needles for several courses 75 after the point intended, and loops and snarls of slack yarn may be formed between the guides 26 and the point at which the yarn is clamped. To obviate these difficulties by placing a constant tension upon the 80 knitting yarns would prevent the operation of the machine in the manner desired and I have, therefore, provided a device to place the idle yarns only under tension, and to keep them under tension until after the said 85 idle yarns have become active yarns and have started to run into the machine, after which the tension is automatically removed. This device consists of a series of tension disks 30 loosely strung upon a bar 31 mounted 90 on an extension 42 of the bracket 3, as by a shoulder and threaded end carrying the nut 32. As many pairs of tension disks 30 are provided as there are movable yarn guide levers, in the present instance four 95 pairs.

As clearly shown in Fig. 2 the bar 31 is placed in such a position as to cause the yarns extending from the fixed guides 27 through the movable guides, which are the 105 apertures in the ends of the levers 5, to the clamp 15, 16 when a lever 5 is out of work, to contact with and enter between a pair of tension disks.

The tension employed is necessarily very 110 light, and to render it delicately adjustable I have placed upon the bar 31, 32 two springs 33, 34 to take against each end of the series of disks. The spring 34 is adjustable by the nut 35 and jam nut 36. The spring 33 is adjustable by the plate 37 which is forked to take around the bar 31 at one end and is bent into a spur 38 to pass through and pivot in a hole in extension 42 at the other end. The set screw 39 having a jam nut 40 115 pressing upon the plate between its ends is employed to adjust the plate 37. Between the two central pairs of disks 30 I place a pin 41 in a hole in the bar 31 to prevent the adjustment of the disks to one side or the 120 other of the planes taken by the moving yarns. The tension disks are of a cupped or flared form easily entered by the yarn.

To aid in the entrance of the yarn, I provide upon each of the yarn guide levers a 125 130

spur 61, which may be bent to coincide with the plane of the tension disks and the particular eyelet 26 carrying the yarn for that guide.

5 The blunt nose of a spur 61 is adapted to enter between and separate the tension disks when the guide carrying the spur is near the end of its movement into its active position, and when the guide is thrown into its inactive position, the spur maintains the tension disks open until after the yarn is between them. I may cut away part of the thickness of the spurs 61 as at 62, to provide free passage for the yarn.

15 The movement of a yarn from its operative position, which is illustrated by a lever 5 carrying the yarn 52 in Fig. 2, to its inoperative position (which is that illustrated by the lever carrying the yarns 50 and 51 in 20 the same figure) will not only carry out the function of removing the yarns from the needles, permitting the yarn to be guided to the center of the surface defined by the needles, clamped and cut, but will also cause the 25 positive insertion of the yarn taken out of work between a pair of the tension disks 30, which occupy a place in line with the yarn in its new position. The tension now placed upon the yarn is sufficient to prevent it from 30 becoming slack under the causes above mentioned. Upon the return of the yarn guide to an operative position the clamping effect of the tension disks is effective during the first part of the movement of the guide and 35 tension is maintained during the remaining movement of the guide lever because of the drag of the bore in the end of the moving guide lever on that part of the yarn between the internal clamp and the free end of the 40 guide lever, until after the needles shall have taken and begun to knit with the hitherto idle yarn, thus maintaining the yarn taut at the moment of insertion. It will be noticed that the position of the tension device 30 is 45 out of the plane now defined by the fixed guide 26 and the aperture in the end of the lever 5, and the running tension upon the yarn takes it out of alignment with the tension disks. At or before this time the clamp 50 16 is opened, sufficient stitches having been formed of the new yarn to firmly embed it in the fabric. The effect of the running tension on the yarn to withdraw it from the tension disks does not accrue, therefore, until after the disks have been opened by a 55 spur 61, and after the needles have taken and knit the yarn.

In case one of the yarn changers is operated as a sectional splicing device to enter its 60 yarn into work and then remove it before a complete revolution of the needles with respect to the feed point, as described in connection with the above mentioned application, the tension devices which I have shown 65 and described in this application are equally

as applicable to hold the idle yarn under the proper tension prior to its insertion and after its removal as they are in the case of those yarn guides operated to change one yarn for another.

70

What I claim is:—

1. In a yarn changing device for knitting machines, a yarn clamp, a tension device, and a fixed yarn guide substantially in line with each other, in combination with a 75 movable yarn guide and means to move it into and out of operation on a line passing between the clamp and the tension device.

2. In a yarn changing device for knitting machines, means having therein a yarn 80 throat for guiding the knitting yarn to the knitting wave, a series of guides relatively fixed with respect to said throat, a series of movable guides between said throat and said fixed guides and a tension device located between one position of the movable guides and said fixed guides.

3. In a knitting machine, a series of yarn 85 guides, and means to move one or more of them at a time from operative to inoperative positions, and the reverse, in combination with means to place the yarn carried by each of the inoperative guides under tension during the time when said yarn is not being knit, and means to cause a yarn 95 restored to operation after knitting with it has begun to be relieved from tension.

4. In a yarn changing device for knitting machines, a yarn clamp, a tension device and a fixed yarn guide, substantially in line 100 with each other, in combination with a movable yarn guide and means to move it into and out of operation on a line passing between the clamp and the tension device, and means to release the tension device at one 105 extreme of the movement of the movable yarn guide.

5. In a yarn changing device for knitting machines a series of independently movable 110 yarn guides and means to move a selected member of the series at a predetermined time into an operative position, in combination with a series of tension devices operative upon the yarns of the inoperative yarn guides, and means operating coincidently 115 with the movement of a yarn guide into operative position to release the tension device for the yarn of that guide.

6. In a knitting machine, sources of yarn supply, a yarn changing mechanism comprising a plurality of yarn guide devices movable into and out of knitting position, means to hold a yarn withdrawn from knitting position by the movements of one of said guide devices, and holding devices for 120 the yarn positioned to be encountered by the yarn between said guide device and the source of yarn supply when the yarn is moved by its guide device.

7. In a knitting machine, knitting needles, 130

sources of yarn supply, a yarn changing mechanism comprising a plurality of levers movable past the surface defined by the knitting needles, means on one side of said surface to clamp the end of a yarn withdrawn from knitting position by the movement of one of said levers, and holding devices for the yarn positioned on the same side of said surface as said clamping means, 10 to be encountered by the yarn between said lever and the source of yarn supply when the yarn is moved by its lever.

8. In a knitting machine, knitting devices and means to feed yarn thereto comprising 15 a plurality of movable yarn guides means to cause some of said guides at predetermined times to move from an operative to an inoperative position, and a tension device relatively fixed with respect to the 20 movable guides in a position to be encountered and engaged by the yarns of such of the guides as are in an inoperative position, in combination with means for clamping the 25 yarns so engaged between the fabric and the movable guide.

9. In a knitting machine, a source of yarn supply, a fixed yarn guide, a yarn-changing device comprising a yarn carrying lever having an end movable into and out of knitting 30 position, means beyond the end of the lever to hold the yarn withdrawn from knitting position by the movement of said lever and holding devices for the yarn between the 35 end of the lever and the fixed yarn guide in a position to receive the yarn when it is withdrawn from knitting position.

10. In a knitting machine, knitting needles, a fixed yarn guide, a source of yarn supply, a yarn changing mechanism comprising a plurality of yarn guides movable 40 from an operative to an inoperative position, means to clamp the yarn withdrawn from knitting position by the movement of one of said yarn guides, and tension devices for the 45 yarn positioned to be encountered by the yarn between said movable yarn guide and the fixed guide when the yarn is moved by its movable guide.

11. In a knitting machine, knitting

needles, a source of yarn supply, a fixed 50 yarn guide, a yarn changing mechanism comprising a plurality of yarn guides movable from an operative to an inoperative position, means to clamp the yarn withdrawn from knitting position by the movement of 55 one of said yarn guides, and a tension device for the yarn between said movable yarn guide and the fixed guide, said tension device being out of the plane defined by the fixed guide and a movable guide in an operative position, whereby the yarn is automatically removed from said tension device 60 after being operatively taken by the needles.

12. In a knitting machine, a yarn feeding device comprising a movable yarn guide and means to cause it to occupy an operative and an inoperative position at predetermined times, a fixed yarn guide, out of the plane of movement of the movable yarn guide, and a tension device between the fixed 70 yarn guide and the movable yarn guide, and substantially in the plane defined by the inoperative position of the movable guide and the fixed guide, whereby a movement to the inoperative position places the yarn under 75 tension, and a movement to the operative position permits the yarn to withdraw from the tension device after it begins to run into the machine.

13. In a yarn tension device for knitting 80 machines, a shaft or bar, means to support said bar, a series of tension disks loosely strung upon said bar, springs at each end thereof, a stop on said bar in the middle of the series of disks, and independent means 85 to adjust the tension of said springs, in combination with movable yarn guides operating in planes between pairs of said disks, and means to operate said guides to enter and remove their yarns from between 90 said disks.

In testimony whereof, I have signed my name to this specification, in the presence of two subscribing witnesses.

HARRY SWINGLEHURST.
